MEANS FOR MAINTAINING CONSTANT COM-
PRESSION IN CYLINDERS OF INTERNAL-
COMBUSTION ENGINES

Grover Hawkins, Shoshoni, Wyo.

Application June 14, 1945, Serial No. 599,382

1 Claim. (Cl. 123—78)

1

My present invention, in its broad aspect, has to do with improvements in means for maintaining a more or less constant compression in cylinders of internal combustion engines, and especially two and four cycle engines of the auto type, whereby tendency to knock is reduced, greater efficiency obtained at low throttle, and greater torque at full throttle, and whereby a very small residue of burned gases remain in a cylinder at the beginning of the intake stroke, hence a lower temperature is maintained on compression and a considerable saving effected in fuel consumed.

In accomplishing the above and other results and advantages, I provide a pressure equalizing chamber communicating through a conduit and valve with the cylinder of the engine, and also communicating through a port with a cylinder having a pressure responsive free piston, and which cylinder also communicates with the cylinder of the engine, so that changes in compression (rise and fall of pressure) in the cylinder of the engine influence the movement of the free piston to regulate both the compression in the cylinder of the engine and in the pressure equalizing chamber, and open and close the port between the pressure equalizing chamber and the cylinder of the pressure responsive free piston.

Other and equally important objects and advantages of my invention will be apparent from the following description and drawings, and it is pointed out that changes in form, size, shape, materials, and construction and arrangement of parts are permissible and within the purview of my broad inventive concept, and the scope of the appended claim.

In the drawings, wherein I have illustrated a preferred form of my invention:

Figure 1 is a vertical section through my invention;

Figure 2 is a section on the line 2—2 of Figure 1;

Figure 3 is a section on the line 3—3 of Figure 2, and

Figure 4 is an enlarged vertical sectional view of the valve shown in Figure 1.

In the drawings, wherein like characters of reference are used to designate like or similar parts:

The numeral 1 designates the cylinder of a conventional internal combustion engine, and 2 the piston. The head 3 of the cylinder is modified in accordance with my invention and has water circulation channels 4 for cooling intake and exhaust valves 5 and 5A, and a spark plug 55

6—see Figures 2 and 3. The head 3 carries a small cylinder 7 communicating through the restricted open base 8 with the main cylinder 1—such restricted base forming an annular shoulder 9 which has a spring valve 10 to cover the ports 9a opening into the cylinder 1. The use of the ports will make the total area of the piston 17 effective rather than just the head 19, and a head 11. The head 11 is flanged, as at 12, for attachment to the flange 14 at the top of the cylinder, and is formed with a depending dome shaped extension 15 within the cylinder and having a rounded end 16. A free piston 17 having a skirt 18 and a head 19 is mounted for movement in the cylinder 7, and the head is provided with an extension fitting in the restricted base 8. The trapped air between the head and skirt portions of piston 17 and the extension 15 and head 11 cushions the upward stroke of the piston, and trapped air between the shoulder 9 and head 19 cushions the downward stroke of the piston.

At a point near the limit of the upward stroke of the piston 17, the cylinder 7 is provided with a port 20 communicating with a pressure equalizing tank or chamber 21, which also communicates through a conduit 22 with the top of cylinder 1; there is an adjustable valve 23 interpolated in the conduit 22. The valve 23 is of the automatic type, and has a cylinder 24 and a piston 25, a connection 26 leads gases under pressure from the main cylinder 1 and has branches 26A at opposite points of the piston 25. Movement of the piston is responsive to pressure beneath it so that gas is transmitted to the compression chamber until a predetermined pressure is reached, whereupon the piston 25 moves to close the connection 26A against the pressure of spring 27 which is adjusted by the screw 28 and cup 29 against which the spring 27 bears. In operation when starting the engine cold, there would be no pressure in tank 21, so at the first compression stroke, free piston 17 would be forced up to the top of its cylinder, and would stay there. Thus the engine would function as a conventional gas engine.

With no pressure in 21 and conduit 22, valve 25 would rest at the bottom of its cylinder under pressure of spring 27, and ports 26a would be open into the annular space in the valve 25 and by the ports therein to the under side of valve 25, directly through conduit 22 to tank 21.

At the compression stroke, a small amount of air will pass through, and after the explosion, more of the now burned gases will rush through. After a few minutes running, the desired pres-

sure as regulated by adjusting screw 28 will be reached in 21, at this point valve 25 will have reached the closed position shown, cutting off ports 26a and preventing further admission of air or gas. If pressure falls in 21 and 22, spring 27 will push valve 25 down, admitting more gases, thus maintaining a constant pressure in tank 21.

Hence, as piston 2 comes up on compression, free piston 17 will not begin to rise until pressure above piston 2 is a little above that in 21.

Thus, as the piston 2 comes up on the compression stroke, the piston 17 rises until the pressure above the piston 17 is a little above the pressure in tank in chamber 21, and by reason of valve 23 pressures will also rise in tank or chamber 21 until all pressures are substantially equalized. Upon the firing of cylinder 1, piston 17 will be driven higher in cylinder 1 to close port 20. As piston 2 descends on the power stroke, pressure in cylinder 1 falls below that in tank 21, and piston 17 descends maintaining a substantially constant pressure in cylinder 1 until it reaches the bottom of its stroke.

The "depending dome" of the head of cylinder 1 is so designed to fit snugly down in free piston 17, thus reducing clearance, and increasing the cushioning effect. With a flat head, the skirts of 17 would hammer against it. When the engine is throttled, piston 17 will only rise part way up in its cylinder; when the explosion occurs, it will be driven up with considerable force, and so this piston must be cushioned as described.

From the foregoing it is believed that the operation and advantages of my invention will be apparent, but it is again emphasized that interpretation of its scope should only be conclusive when made in the light of the subjoined claim.

I claim:

Means for maintaining a constant compression in a cylinder of an internal combustion engine, comprising a pressure equalizing tank having an adjustable valved communication with the cylinder to receive gases therefrom to a predeter-

mined pressure in the tank, said adjustable valved communication including a conduit, a valve having a pressure responsive piston controlling passage of gases through the valve, a spring against which the valve operates and means for adjusting the tension of the spring on the valve, a cylinder communicating with the cylinder of the engine and having a port communicating with the pressure tank, a free piston in the cylinder responsive to pressures in the tank and the engine cylinder, and opening and closing the port at points in its stroke whereby to be moved down by pressure in the tank and moved up by pressure in the engine cylinder, said free pressure responsive piston having a head and a skirt, the skirt opening and closing the port, and the cylinder of the free piston having a head with a depending dome between which and the piston air is trapped to cushion the upward stroke of the piston and air annular shoulder at the lower end of the cylinder between which and the piston air is trapped to cushion the downward stroke of the piston relatively spaced ports in said shoulder and a spring valve adapted to control the ports to balance the piston during downward stroke thereof.
